[57] CLAIM

The ornamental design for a merchandising display wall
standard, as shown and described.

DESCRIPTION

FIG. 1 is a front perspective view of a merchandising
display wall standard showing our new design, the rear
being plain and unornamented, the broken line showing
of walls is for illustrative purposes only and form no
part of the claimed design;FIG. 2 is a cross-sectional view taken along line 2—2 of
FIG. 1; andFIG. 3 is an enlarged fragmentary front perspective
view thereof.Fig. 1
